(57) **CLAIM**

The ornamental design for a surgical stent, as shown and described.

DESCRIPTION

FIG. 1 is a top perspective view of another embodiment of a surgical stent showing our new design;
FIG. 2 is a front side elevational view thereof;
FIG. 3 is a rear side elevational view thereof;
FIG. 4 is a right side elevational view thereof;
FIG. 5 is a left side elevational view thereof;
FIG. 6 is a top plan view thereof;
FIG. 7 is a bottom plan view thereof;
FIG. 8 is a top perspective view of another embodiment of a surgical stent showing our new design;
FIG. 9 is a front side elevational view thereof;
FIG. 10 is a rear side elevational view thereof;
FIG. 11 is a right side elevational view thereof;
FIG. 12 is a left side elevational view thereof;
FIG. 13 is a top plan view thereof; and,
FIG. 14 is a bottom plan view thereof.
It is noted that the aspects shown in broken lines do not form part of the claimed design.
